(57) **CLAIM**

The ornamental design for a high frequency signal distributor, as shown and described.

DESCRIPTION

FIG. 1 is a top, front, right side perspective view of a high-frequency signal distributor showing my new design; FIG. 2 is a bottom, front, left side perspective view thereof; FIG. 3 is a top plan view thereof;

FIG. 4 is a real elevational view thereof;

FIG. 5 is a front elevational view thereof;

FIG. 6 is a bottom plan view thereof;

FIG. 7 is a left side elevational view thereof;

FIG. 8 is a right side elevational view thereof;

FIG. 9 is a top, front, right side perspective view of the high-frequency signal distributor shown in FIG. 1 shown in an open position;

FIG. 10 is a top plan view thereof;

FIG. 11 is a rear elevational view thereof;

FIG. 12 is a front elevational view thereof;

FIG. 13 is a bottom plan view thereof;

FIG. 14 is a left side elevational view thereof; and,

FIG. 15 is a right side elevational view thereof.
